UNITED STATES PATENT OFFICE

171,740

BIRD CAGE

Bernard Yellin, Chicago, Ill., assignor to Bernard Edward Co., Chicago, Ill., a corporation of Illinois

Application January 5, 1953, Serial No. 23,000

Term of patent 14 years

(Cl. D31—2)

To all whom it may concern:

Be it known that I, Bernard Yellin, a citizen of the United States, and a resident of the city of Chicago, county of Cook, State of Illinois, have invented a new, original, and ornamental Design for a Bird Cage, of which the following is a specification, reference being had to the accompanying drawings, forming a part thereof in which:

Figure 1 is a perspective view of a bird cage showing my new design;

Figure 2 is an end elevational view of the same;

Figure 3 is a top plan view of the same, and

Figure 4 is a side elevational view of the same.

The appearance of the end opposite Figure 2 is substantially the same as that of Figure 2; and the appearance of the side opposite Figure 4 is substantially the same as that of Figure 4.

I claim:

The ornamental design for a bird cage, substantially as shown and described.

BERNARD YELLIN.
